DESIGN FOR ILLUMINATED SIGNS.

Design No. 11,165, dated April 15, 1879.

UNITED STATES PATENT OFFICE.

BENJAMIN F. CHASE, OF BALTIMORE, MARYLAND.

DESIGN FOR ILLUMINATED SIGNS.

Specification forming part of Design No. **11,165**, dated April 15, 1879; application filed February 18, 1879.
[Term of patent 14 years.]

To all whom it may concern:

Be it known that I, BENJAMIN F. CHASE, of Baltimore city, State of Maryland, have originated a certain Design for Signs, of which the following is a full, clear, and exact description, reference being had to the accompanying photographic illustration, making part of this specification.

A represents the body of the sign, consisting of a frame-work containing front and side panels of glass bearing suitable inscriptions, and surmounted in various parts by ornaments *a a*. B is a central bar, projecting from the sides of the sign, having also front and side panels, *b*, and bearing the prominent word.

The signs are designed to be illuminated by night by gas-jets inside.

What I claim is—

The design for illuminated signs herein described, consisting of the body A, having front and side panels, *a'*, and projecting bar B, also provided with front and side panels, *b*, substantially as described.

BENJAMIN F. CHASE.
